N. 26.317.

Martin Winger's
Bark-Shaving Machine.

Patented Nov. 29. 1859.

UNITED STATES PATENT OFFICE.

MARTIN WINGER, OF VOGANNSVILLE, PENNSYLVANIA.

MACHINE FOR SHAVING BARK.

Specification of Letters Patent No. 26,317, dated November 29, 1859.

To all whom it may concern:

Be it known that I, MARTIN WINGER, of Vogansville, in the county of Lancaster and State of Pennsylvania, have invented a new and useful machine for the purpose of shaving off the rough crust or epidermis from oak-bark, preparatory to the manufacture of quercitron, used and exported for dyeing purposes; and I do hereby declare that the following is a full, clear, and exact description of the construction and operation of the same, reference being had to the annexed drawings, making a part of this specification, in which—

15 Figure 1, is a perspective view of the entire machine. Fig. 2: Nos. 1, 2 and 4 the three concave sided cast iron rollers, detached, No. 3, the curved knives mounted on rollers affixed to the axis which bears the strap pulleys D, C. T is the adjusting frame. Fig. 3 is an end view of Fig. 6. Fig. 4 shows the sliding frame G, the slides X, and grooved or slotted uprights F, fixed to the side frame Z of the machine, with the 20 bearing pulley h, mounted in the vertical shaft H. Fig. 5, is one of the curved shaving knives V; Fig. 6, a side view of the broad belt W of leather to which the plano-convex cross pieces O, O, are attached forming an endless platform around the flanged outside drums Q with intermediate small carrying rollers, P, and a central flanged guiding roller P', as shown.

25 Power, by means of a horse or steam is applied to the larger strap pulley D, the shaft of which supports and revolves the shaving drum No. 3. There is also a smaller strap pulley C, on this shaft, connected by a strap to the larger pulley B. Behind this 30 pulley B on its shaft is a small cogwheel (not seen but traced on the drawing) geared into a large cogwheel on the shaft of the front flanged drum Q which gives motion to the endless revolving platform O, O, W.

45 The operation is thus: The bark of any size or thickness is laid with its concaved side upon the convex portion of the platform O, which conveys it under the heavy pressing roller 1, so fixed in the uprights E, as to

give it play and accommodate itself to the 50 bark, however thick. This roller presses the bark of a regular curve on the endless platform, which has short retaining pegs in each piece, that enter the fiber or inside of the bark. There is, between this and the conducting roller 2, a bearing pulley h, as 55 stated, supported on the vertical shaft H, to prevent the possibility of the bark from turning upward as it passes through under the pressing roller 1, to the conducting roller 60 No. 2, which latter presents it to the action of a series of knives V, mounted as shown by No. 3, Fig. 2. These mounted knives have their axes supported in the frame T, inside the external frame K, slotted so as to allow 65 the shaft or axis to move up and down. On the top of the frame T, are two square headed screws N, surmounted by cogged pulleys M, geared into a cogged wheel L, on top S, of the upright I. The screws enter female screws in the top V, of the uprights K, and thus by moving the wheel L, the knives can be raised and lowered, to adapt them to the diverse thicknesses, in the pieces of bark to be operated on. The convex platform O, 70 O, W, is adapted to the natural concavity of the bark, thereby preventing its splitting when pressed into a uniform curve, to which the knives are also adapted, so that this 75 machine can perform the work of many 80 hands when employed in the ordinary manner with drawing knives as is customary.

Machines may have been used, to press bark flat and shave them, and in some respects perhaps similar in construction. 85

I do not simply claim the pressing and shaving by machinery nor the gearing employed separately considered.

What I claim as my invention and desire to secure by Letters Patent is— 90

The combination of the convex traveling bed O, W, with the rotary knives V, and pressure rollers 1, 2 4 and h in the manner and for the purpose set forth.

MARTIN WINGER.
